UNITED STATES PATENT OFFICE.

FREDERICK W. COLE, OF NEWTON, MASSACHUSETTS.

LOCAL-ALARM DOOR FOR SIGNAL-BOXES.

SPECIFICATION forming part of Letters Patent No. 552,746, dated January 7, 1896.

Application filed March 9, 1895. Serial No. 541,120. (No model.)

To all whom it may concern:

Be it known that I, FREDERICK W. COLE, of Newton, in the county of Middlesex and State of Massachusetts, have invented an Improvement in Local-Alarm Doors for Signal-Boxes, of which the following description, in connection with the accompanying drawings, is a specification, like letters on the drawings representing like parts.

10 This invention has for its object to construct a local-alarm door for fire-alarm and other signal-boxes, whereby a local alarm is given before the fire-alarm can be transmitted.

Local-alarm mechanism for fire-alarm or 15 other electric signal-boxes have been made in different ways; but many of them are insufficient for the reason that a box-tamperer can, by operating them slowly, produce so little noise as not to call the attention of passers-by, and hence can thereafter tamper with the box.

My invention is herein represented as adapted to be applied to a box wherein the operating-lever of the signaling mechanism is accessible upon opening the door, and the local-alarm mechanism is connected with the bolt or lock of said door, so that as it is operated the bolt will be withdrawn or the lock operated, permitting the door to be opened.

30 In carrying out this invention the striking-lever of a local gong is operated by a toothed wheel to which is connected an actuating-spring, the other end of said spring being connected with a knob or handle, which upon 35 being turned extends said spring and stores up sufficient energy to turn the toothed actuating-wheel. A locking device is provided for the actuating-wheel, which holds it at rest while the knob or handle is being turned to 40 extend the actuating-spring, and which locking device is tripped by a tripping-finger operated by said knob or handle to let off the actuating-wheel before the bolt of the door is withdrawn, and as soon as said actuating-wheel is thus released it operates the striking-lever, and during such time is absolutely out 45 of the control of the man at the box.

While I have herein shown the local-alarm mechanism as adapted to withdraw the bolt 50 of the lock, that the door may be opened and subsequently the alarm turned in, it is ob-

vious that it may be connected with the operating-lever of the signaling mechanism in any usual way.

The parts are furthermore so arranged that 55 the bolt of the door may be slid with an outside detachable key in the common way, whenever desired, without operating the local alarm.

Figure 1 shows a rear side view of a local-alarm door for fire-alarm boxes; Fig. 2, a vertical section of the local-alarm door shown in Fig. 1; Fig. 3, an enlarged view of several of the operating parts of the local-alarm mechanism.

The door A of any usual shape and size is recessed sufficiently to receive the local-alarm mechanism. The gong a is attached to a post by a screw a', and the striking-lever a² is secured to a shaft or arbor of a pallet a³, which co-operates with or is moved by a toothed actuating-wheel a⁴. The toothed wheel a⁴ is placed loosely upon the spindle a⁵ to which the knob or handle a⁶ is secured, and a lug a⁷ is formed on said toothed wheel, adjacent the 60 spindle a⁵, which lug enters a gap cut in a hub a⁸ secured to said spindle a⁵ by a set-screw a⁹. A coiled spring b surrounds the hub a⁸, one end of which is attached to said hub, and the other end to a pin b² on the frame, said spring 65 acting as a return-spring to restore the knob a⁶ and connected parts to their normal position of rest. A ratchet-wheel c is secured to the frame, and a pawl c' is pivotally connected to the toothed actuating-wheel a⁴, a suitable 70 spring being provided for normally pressing said pawl into engagement with the ratchet-wheel. This pawl and ratchet constitute a locking device for the toothed actuating-wheel a⁴. The pawl c' has a projection c', which lies 75 in the path of movement of a tripping-finger d formed on the hub a⁸, so that after the knob a⁶ has been turned a certain distance said finger d will strike and disengage the pawl c'. A spring e is attached at one end to the tripping-finger d, and at the other end to the actuating-wheel a⁴, and as the knob a⁶ is turned the spring e will be extended while the actuating-wheel is held at rest, and such movement of the parts may continue until the pawl 80 c' is disengaged from the ratchet-wheel, and the toothed wheel having been thus released 85

it quickly turns, operating the striking-lever and violently sounding the gong. The hub a^8 has also formed on it a crank-arm f which is turned therewith, and which after the handle has been turned about half round strikes one arm of a bell-crank lever f' pivoted to the frame and held in its normal position of rest by a spring. The other arm of said bell-crank lever engages a bolt f^3 of the door, 10 which is withdrawn by said bell-crank lever being turned by the crank-arm f .

Thus it will be seen that the local alarm will respond when the knob or handle has been turned a certain distance, and when it begins 15 to act is absolutely out of the control of the man at the box, and that subsequently the bell-crank lever f' is moved to withdraw the bolt. The door may then be opened and the alarm pulled in. It will also be observed that 20 the bell-crank lever f' is independent of the local-alarm mechanism, so that a key may be introduced and the bolt withdrawn, as usual, without disturbing the local-alarm mechanism. Hence a person having a key can open 25 the door without causing the local alarm to respond.

The notches on the wheel c are arranged quite close together, so that the handle can be turned but a short distance before the local-alarm mechanism is let off, and if the knob 30 is continuously turned the local alarm will continue to respond, and can be more or less accelerated at the option of the man at the box. Furthermore, the gap in the hub is 35 made of such length that the knob can be turned with relation to the wheel but a little more than is required to trip the locking device, and thereafter the power applied is used in accelerating the progress of the wheel.

40 If a single notch is employed in wheel c it is possible to turn the knob and trip the locking device but once, and then hold the knob at rest a short time while the local alarm is sounding, and then to further turn the knob 45 slowly, making but little noise; but by providing several notches, if the knob should be so slowly turned the actuating-spring will advance the wheel a^4 sufficiently for the pawl c' to drop into another notch, and in such case 50 the wheel a^4 will again be held at rest while its actuating-spring is again extended. Hence it is impossible to turn the knob slowly and by making but little noise tamper with the box. It will be further observed that by providing the lug a^7 on the actuating-wheel a^4 , 55 which enters a gap in the hub a^8 , a positive connection is insured under all conditions between the knob and actuating-wheel, and the

wheel always operates before the door can be opened.

60

I claim—

1. The toothed actuating wheel a^4 for the striking lever, combined with a locking device restraining it from rotation, an actuating spring therefor, a knob or equivalent device 65 for extending said spring, storing up energy for actuating the wheel, and means for releasing said locking device after the knob has been turned a predetermined distance.

2. The door A, its bolt, toothed actuating 70 wheel a^4 for the striking lever of a gong, actuating spring therefor, knob accessible at the outside of the box, connected with and adapted to extend said actuating spring, a locking device for the toothed actuating wheel which 75 holds it at rest while the spring is being extended, a tripping finger therefor operated by the knob, and arm f also connected with and turned by said knob which withdraws the bolt, 80 substantially as described.

3. The local alarm mechanism comprising the actuating wheel a^4 for the striking lever of the gong, pawl c' , carried by it, toothed wheel c , knob a^6 , tripping finger carried by 85 it, and an actuating spring connecting the wheel a^4 with the knob.

4. The combination of the toothed actuating wheel a^4 , a locking device therefor, independent handle a^6 , spring e connecting the handle with the wheel, which when extended 90 by said handle stores up energy to actuate the wheel, means for releasing said locking device after the handle has been turned a predetermined distance, and the lug a^7 on the wheel which enters a gap in the hub of the 95 handle, permitting a limited independent movement of the handle, but insuring positive operation of the actuating wheel before the door can be opened.

5. A door, bolt therefor, pivoted spring controlled bell-crank lever f' , one arm of which engages said bolt, local alarm mechanism operated by a knob accessible from the outside of the door, and crank arm f also operated by said knob, which when turned engages the 105 other arm of said bell-crank lever, to slide the bolt, and a detachable key for also sliding said bolt without operating the local alarm mechanism.

In testimony whereof I have signed my 110 name to this specification in the presence of two subscribing witnesses.

FREDERICK W. COLE.
